UNITED STATES PATENT OFFICE.

AUGUSTUS F. KLASING, OF CHICAGO, ILLINOIS, ASSIGNOR TO THE KLASING CAR BRAKE COMPANY, A CORPORATION OF COLORADO.

LIFTING DEVICE.

1,420,555.

Specification of Letters Patent. Patented June 20, 1922.

Application filed June 7, 1919. Serial No. 302,565.

To all whom it may concern:

Be it known that I, AUGUSTUS F. KLASING, of Chicago, Cook County, Illinois, a citizen of the United States of America, have invented a certain new and useful Improvement in Lifting Devices, of which the following is a specification.

My invention relates to a power applying or lifting device which may be used for various purposes, and has for its object to provide certain novel and improved mechanism whereby longitudinal movement, a lifting movement particularly, may be given to a rack member and such member held, releasably, in the position to which it is moved. A further object is to provide means whereby the holding device is automatically reset to its operative position by return movement of the rack member when released.

20 In the drawings—

Fig. 1 is a front elevation of a lifting device or power applying mechanism constructed in accordance with my invention.

Fig. 2 is a side elevation of the same.

25 Fig. 3 is a vertical sectional view on line 3—3 of Fig. 1, and

Fig. 4 is a sectional plan on line 4—4 of Fig. 2.

The device as illustrated comprises a housing 1 having lugs 2 for attachment to the structure on which the device is used. The housing is formed on one of its inner surfaces with a rack 3. Within the housing is a vertically movable rack bar 14 formed with

30 teeth 16 adapted to be engaged by a rolling or floating pinion 30 which travels along the fixed rack 3. Preferably anti-friction balls 5 are arranged in raceways 4 formed in the housing, against which balls bear the surfaces 17 of the rack bar 14. The pinion 30 is secured to a ratchet wheel 32, the latter being provided with a hub 33 which extends through an elongated slot 11 in the housing. The hub has a squared portion 20 engaging

45 the pinion 30, the parts being held together by a bolt 31. On the inner side of the pinion 30 is a washer 39 adapted to project into an elongated slot 40 in the housing opposite slot 11. Pivotally arranged with reference

50 to the ratchet wheel 32 and held in place by the bolt 31 is an operating lever 34 to which is attached by pivot pin 35 a pawl 36 adapted to coact with the ratchet wheel 32. The pawl is formed with a tail piece 37 and

the housing 1 with a flange 9 disposed parallel to the upward travel of the pawl against which the pawl is pressed, to disengage it from the ratchet when the lever is given a reverse, that is to say, a downward movement. The lever is preferably formed with 60 a housing 38 to protect the ratchet wheel.

A detent device is provided for holding the rack bar 14 at any desired elevation. This device comprises two racks or sets of holding teeth 8 formed on the housing 1 on opposite sides of the vertical slot 6 thereof and a double detent 21 pivoted to and straddling a projection 15 on the rack bar 14, said detent being formed with toothed portions 23 adapted to engage the teeth 8. A 70 tripping device 25 which has a yoke portion 26 extending around the detent 21 is mounted on the same pivot pin 19 employed for pivoting the detent to projection 15.

The tripping device is formed with an internal slot 28 into which projects the transverse web 22 connecting the two legs 24 of the detent. The tripping device 25 is formed with a stud 29 adapted to come into contact with a cam 13 formed on the housing when 75 the rack bar approaches the lower limit of its travel to turn the trip member 25 to a position in which it will bring the detent into operative contact with the teeth 8. The trip member is formed for convenience with 80 a handle 27 for setting it to a position in which it will disengage the detent from the holding teeth 8.

Summary of operation: The rack 14 is raised, step by step, by intermittent oscillations in an upward direction of the lever 34. At the beginning of each reverse movement of the lever detent 21 engages the holding teeth 8 to prevent the rack bar from falling and the pawl 36 is disengaged from the 95 ratchet 32 by the tail piece 37 of the pawl coming into contact with flange 9 on the housing. To release the rack bar the trip member 25 is tilted forwardly from the position shown in the drawings so that its weight 100 is brought to bear against the detent 21, that is, the shoulder at the left hand end of slot 28 (Fig. 3) is brought to bear against the web 22 of the detent. This does not force the detent from the holding teeth 8 (assuming a downward stress on the rack bar) but as soon as the rack bar has been relieved of this stress, which is accomplished by slight

upward or forward movement of the operating lever, the detent, under weight of the tripping device, will drop and be held away from the teeth 8. The operator releases the 5 lever and the pull on the rack bar transmitted to the lever through the ratchet and pawl mechanism, imparts a reverse movement to the lever which causes the tail 37 of the pawl to come against the flange 9 so as to 10 disengage the pawl from the ratchet wheel 32. As the rack bar drops the lever is disconnected from the ratchet so that it receives no appreciable reaction. It will be observed that the automatic disengagement of the 15 lever from the ratchet takes place immediately for all working positions of the lever.

As rack bar 14 approaches the limit of its downward movement the stud 29 comes into contact with cam 13 and the tripping 20 device 25 and detent 21 are returned to their holding positions.

What I claim and desire to secure by Letters Patent is:—

1. In a lifting device a fixed rack, a floating gear coacting with said rack, a movable member coacting with said gear, adapted to be given multiplied movement thereby; a housing adapted to enclose the moving parts; a step by step actuating means associated with the floating gear; means for holding the movable member in the raised position; means to automatically release the holding means and return the movable parts to initial position instantaneously; means to 35 automatically reset the holding means simultaneously with the return of the parts to initial position

2. In combination a fixed gear rack, a movable spur gear operable upon said rack, 40 a movable rack coacting with said movable gear, a bearing for said movable rack, means associated with said movable rack to hold the same in raised position; means associated with the holding means adapted to 45 maintain the same in engagement and adapted to automatically release the holding means from engagement; and step by step means to actuate the spur gear and the movable rack.

3. A lifting device, comprising a frame provided internally with a fixed rack; internal anti-friction bearings, a sliding rack adapted to slide upon the anti-friction bearings; a spur gear coacting with the fixed 55 rack and the sliding rack adapted to secure multiplied lifting; step by step actuating means associated with the movable spur gear; means associated with the sliding rack and means coacting therewith associated 60 with the fixed rack for providing a locking engagement of the sliding rack at varying elevations; an actuating means associated with the spur gear; automatic means to release the locking engagement for return of the sliding rack to initial position; and auto-

matic means to reset the locking engagement means simultaneously with the return of the sliding rack to initial position.

4. In combination a spur gear mounted for rotation and bodily movement, a fixed 70 rack and a movable rack engaged by said gear, an actuating mechanism transmitting movement step by step to the movable gear; means associated with the movable rack and means, coacting therewith, associated with the fixed rack for holding the movable rack in raised position; means adapted to be set to release the holding means for return of the movable rack to initial position through 75 operation of the actuating means.

5. In combination a spur gear mounted for rotation and bodily movement, a fixed rack engaged by said gear, a sliding rack coacting with said gear, a power applying lever associated with said spur gear, a pawl-and-ratchet mechanism transmitting the movement of the lever to said gear; means associated with said lever to automatically release the pawl from its ratchet engagement at any point of the movement of the spur 90 gear along the line of the fixed rack; and locking means operably associated with the movable rack and with the fixed rack.

6. In a device for the purposes described a lifting means consisting of a fixed rack, a floating spur gear and a movable rack meshing and coacting with the spur gear; means for giving step by step rotary movements to the spur gear; a detent associated with the movable rack; retaining means engageable 100 by the detent which is associated with the fixed rack; means to automatically release the movable rack from locking engagement at any point of elevation to allow the same to fall; means to automatically reset the 105 locking mechanism simultaneously with the return of movable parts to initial position.

7. In a device of the character described a housing, a fixed rack in said housing; anti-friction bearings operable upon the walls 110 of the housing opposite to said rack; a sliding rack adapted to slide upon the anti-friction bearings; a bodily movable spur gear mounted to engage the fixed rack and the movable rack; power applying means associated with the spur gear; means for locking the movable rack at any point of its travel; means to instantaneously release the movable rack for return to initial position; automatic means to reset the locking mechanism 115 simultaneously with the return of the movable rack to initial position.

8. In combination, a rectangular housing, a fixed rack upon one of the internal sides of said housing, an anti-friction bearing operable upon the opposite internal side of the housing, a spur gear engaging the said rack, a sliding rack engaging said gear, a slot 125 upon the face of said housing opposite the fixed rack adapted to permit the travel of 130

- the sliding rack, means for propelling the spur gear; means upon said housing to limit the travel of the spur gear in either direction of its propulsion; means to automatically lock the sliding rack at any position of its travel; means to release the locking means; a lug associated with the housing and a pin associated with the locking mechanism adapted to cause an automatic return of the locking mechanism to locking position when the lifting mechanism is returned to its initial position.
9. In apparatus of the character described, the combination of a driven element, a driving member provided with releasable means for engaging the driven element, a detent for holding the driven element in the position to which it is moved, means adapted to be set to render said detent inoperative as soon as stress on the driven element is relieved by forward movement of the driving member, means actuated upon reverse movement of the driving member for disengaging the driving member from the driven element, and means whereby the detent is automatically reset to its holding position at the completion of the return movement of the driven element.
10. In apparatus of the character described, the combination of a driven element provided with ratchet teeth, a driving member having a pawl for engaging said teeth, a detent for holding the driven element in the position to which it is moved, means adapted to be set to render said detent inoperative as soon as stress on the driven element is relieved by a forward movement of the driving member, means actuated upon reverse movement of the driven member and at any working position thereof for immediately disengaging the pawl from said ratchet teeth, and means whereby the detent is automatically re-set to its holding position at the completion of the return movement of the driven element.
11. In apparatus of the character described, the combination of a movable rack, a pinion to engage said rack and impart movement thereto, an operating lever, a pawl and ratchet mechanism associated with the pinion and lever for giving step by step rotation to the pinion, a detent to hold the rack in the extended position, a trip member which may be set to render the detent inoperative as soon as the rack is relieved of stress by forward movement of the lever, and means whereby a reverse movement of the lever disengages the pawl from said ratchet.
12. In apparatus of the character described, the combination of a movable rack, a pinion to engage said rack and impart movement thereto, an operating lever, a pawl and ratchet mechanism associated with the pinion and lever for giving step by step rotation to the pinion, a detent to hold the rack in the extended position, a trip member which may be set to render the detent inoperative as soon as the rack is relieved of stress by forward movement of the lever, and means whereby a reverse movement of the lever disengages the pawl from said ratchet.
13. In apparatus of the character described, the combination of a movable rack, a pinion to engage said rack and impart movement thereto, an operating lever, a pawl and ratchet mechanism associated with the pinion and lever for giving step by step rotation to the pinion, a detent to hold the rack in the extended position, a trip member which may be set to render the detent inoperative as soon as the rack is relieved of stress by forward movement of the lever, and means whereby a reverse movement of the lever, at any working position thereof, immediately disengages the pawl from the ratchet.
14. In apparatus of the character described, the combination of a stationary rack, a movable rack, a pinion having interengagement with said racks and movable along the stationary rack, a ratchet wheel fixed to said pinion, an operating lever provided with a pawl to engage said ratchet wheel, a detent to hold the movable rack in the extended position, a trip member adapted to be set to render the detent inoperative as soon as the movable rack is relieved of stress by forward movement of the lever, and means whereby a reverse movement of the lever disengages the pawl from the ratchet.
15. In apparatus of the character described, the combination of a stationary rack, a movable rack, a pinion having interengagement with said racks and movable along the stationary rack, a ratchet wheel fixed to said pinion, an operating lever having a pawl pivoted thereto to engage said ratchet, a detent to hold the movable rack in the extended position, a trip member which may be set to render the detent inoperative as soon as the rack is relieved of stress by forward movement of the lever, and means providing a surface extending parallel to the travel of said pinion with which said pawl is engaged, on reverse movement of the lever, to disconnect it from the ratchet.
16. In apparatus of the character described, the combination of a stationary rack, a movable rack, a pinion having interengagement with said racks and movable along the stationary rack, a ratchet wheel fixed to said pinion, an operating lever having a pawl pivoted thereto to engage said ratchet, a detent to hold the movable rack

- in the extended position, a trip member which may be set to render the detent inoperative as soon as the rack is relieved of stress by forward movement of the lever, 5 means providing a surface extending parallel to the travel of said pinion with which said pawl is engaged, on reverse movement of the lever, to disconnect it from the ratchet, and means operative, when the movable rack 10 on release reaches the end of its travel, to re-set said detent and tripping member to their holding positions.
17. In apparatus of the character described, the combination of a housing having an internal, vertically disposed rack, a rack bar movable upwardly through said housing, a pinion interposed between said rack and rack bar and adapted to travel along the rack, a ratchet wheel fixed to said 15 pinion, an operating lever provided with a pivot pawl for engagement with said ratchet wheel, a detent pivoted to said rack bar, a series of holding teeth on the housing engageable by said detent, a tripping device 20 pivoted to the rack bar and adapted to be set either to maintain the detent in engagement with the holding teeth to move the same away from the holding teeth, means on the housing providing a surface extending 25 parallel to the travel of the pinion for disengaging the pawl from the ratchet on reverse movement of the lever, and a projection on the housing adapted to engage said tripping member and re-set the same and 30 said detent to their operative positions when the rack bar on release reaches the lower limit of its travel.
18. In apparatus of the character described, the combination of a rack bar movable in the direction of its length, driving 35 means to impart movement to the rack bar comprising a pinion to engage the rack bar and a lever to rotate the pinion, a detent to hold the rack bar in its extended position, a trip member which may be set to render the 40 detent inoperative as soon as the rack bar is relieved of stress by a forward movement of the lever, and means whereby a reverse
- movement of the lever frees the rack bar from the driving means to allow the same 50 to return to the position from which it was moved.
19. In apparatus of the character described, the combination of a longitudinally movable rack bar, a lever provided with 55 means for imparting movement to the rack bar when said lever is rotated in one direction, which means releases the rack bar when the lever is rotated in the other direction, a detent for holding the rack bar in the position to which it is moved, and means adapted to be set to render said detent inoperative as soon as stress on the rack bar is relieved by another forward movement of the lever. 60
20. A lifting device comprising a bar, means for moving said bar longitudinally to exert a pull, mechanism engaging said bar for preventing reverse movement thereof, means for releasing said mechanism to permit a reverse movement of said bar, and means for automatically re-engaging said mechanism with said bar when the same has reached the limit of its reverse movement. 65
21. A lifting mechanism comprising a ratchet bar, a dog engaging said bar for preventing reverse movement thereof, means for disengaging said dog, and means independent of said disengaging means for automatically causing the re-engagement of said dog with said bar when the ratchet bar returns to its initial position. 70
22. A lifting mechanism comprising a housing, a rack bar movable longitudinally in said housing, a rack on said bar, a rack on said housing opposite the first named rack, a floating gear between said racks and meshing therewith, a ratchet attached to said gear, an operating handle pivoted to the axis of said gear and rack and operatively 85 engaging therewith for rotating the same by means of a pawl, and a tripping surface on said housing adjacent said pawl for tripping the same. 90

Signed at Chicago, Illinois, June 2, 1919. 95
AUGUSTUS F. KLASING.
